[57] CLAIM

The ornamental design for a boat motor mount, as shown and described.

DESCRIPTION

FIG. 1 is a right side elevational view of the first embodiment of a boat motor mount showing my new design, the left side elevational view being a mirror image thereof;

FIG. 2 is a top plan view thereof;

FIG. 3 is a bottom plan view thereof;

FIG. 4 is a front elevational view thereof;

FIG. 5 is a rear elevational view thereof;

FIG. 6 is a right side elevational view of a second embodiment of the boat motor mount, the left side elevational view being a mirror image thereof;

FIG. 7 is a top plan view of FIG. 6;

FIG. 8 is a bottom plan view of FIG. 6;

FIG. 9 is a front elevational view of FIG. 6; and,

FIG. 10 is a rear elevational view of FIG. 6.

The broken lines are for illustrative purposes only and form no part of the claimed design.
